(57) **CLAIM**

The ornamental design for a brace, as shown and described.

DESCRIPTION

FIG. 1 is a front view of a brace.

FIG. 2 is a back (rear) view of the brace.

FIG. 3 is a right side view of the brace.

FIG. 4 is a left side view of the brace.

FIG. 5 is a top view of the brace.

FIG. 6 is a bottom view of the brace.

FIG. 7 is a perspective view of the brace.

FIG. 8 is a front perspective view of the brace in a state of use; and,

FIG. 9 is a rear perspective view of the brace in a state of use.

The dashed lines depict portions of the brace that form no part of the claimed design. The dot-dot-dash lines depict environmental subject matter and form no part of the claimed design.

This brace assists in wearer's actions such as lifting, and helps the wearer to maintain his/her posture, thereby reducing wearer's burden on his/her back and waist.
